(57) **ABSTRACT**

A display control device includes: a changing unit changing a two-dimensional location representing locations in a horizontal direction and an orthogonal direction of each of a plurality of objects having different depths for a display screen of a display unit according to a direction in which a user views the display unit; a transparency adjusting unit for adjusting transparency for each of the plurality of objects; and a display control unit for displaying the plurality of objects in which the two-dimensional location is changed and the transparency is adjusted on the display unit, so as to overlap each other.

DISPLAY CONTROL DEVICE, DISPLAY CONTROL METHOD, AND PROGRAM

BACKGROUND

The present disclosure relates to a display control device, a display control method, and a program, and particularly relates to a display control device, a display control method, and a program in which it is possible to easily recognize objects such as windows displayed on a rear surface when displaying the objects overlapping each other on a screen.

For example, in a personal computer, a plurality of windows may be displayed on a display (Japanese Unexamined Patent Application Publication No. 2000-155635).

In the personal computer, for example, by displaying a plurality of windows overlapping each other according to a user operation, a region for displaying other windows may be secured on the display.

SUMMARY

However, when displaying a plurality of windows overlapping each other in the foregoing personal computer, it is difficult to see windows displayed on a rear surface through windows displayed on a front surface.

It is desirable that it be possible to easily recognize objects such as windows displayed on a rear surface when displaying the objects overlapping each other on a screen.

According to an embodiment of the present disclosure, there is provided a display control device including: a changing unit for changing the two-dimensional location representing locations in the horizontal direction and the orthogonal direction for each of a plurality of objects having different depths for a display screen of a display unit according to the direction in which a user views the display unit; a transparency adjusting unit for adjusting the transparency of each of the plurality of objects; and a display control unit for displaying the plurality of objects in which the two-dimensional location is changed and the transparency is adjusted overlapping each other in the display unit.

A detecting unit for detecting an object of the plurality of objects to which the user focuses may be further provided, and the transparency adjusting unit may adjust the transparency of the object to which the user attends to be lower than that of an object to which the user does not focus.

The transparency adjusting unit may adjust respective transparencies of the plurality of objects to have different values.

According to another embodiment of the present disclosure, there is provided a display control method of a display control device for displaying an object on a display unit, the method by the display control device including: changing a two-dimensional location representing locations in the horizontal direction and the orthogonal direction of each of a plurality of objects having different depths for a display screen of a display unit according to the direction in which a user views the display unit; adjusting the transparency of each of the plurality of objects; and displaying the plurality of objects in which the two-dimensional location is changed and the transparency is adjusted overlapping each other in the display unit.

According to still another embodiment of the present disclosure, there is provided a program allowing a computer to function as a changing unit for changing a two-dimensional location representing locations in the horizontal direction and the orthogonal direction for each of a plurality of objects having different depths for a display screen of a display unit

according to the direction in which a user views the display unit; a transparency adjusting unit for adjusting the transparency for each of the plurality of objects; and a display control unit for displaying the plurality of objects in which the two-dimensional location is changed and the transparency is adjusted overlapping each other in the display unit.

According to another embodiment of the present disclosure, the two-dimensional location representing locations in the horizontal direction and the orthogonal direction for each of a plurality of objects having different depths for a display screen of a display unit are changed according to the direction in which a user views the display unit; the transparency of each of the plurality of objects is adjusted; and the plurality of objects in which the two-dimensional location is changed and the transparency is adjusted are displayed overlapping each other in the display unit.

According to the embodiments of the present disclosure, it is possible to easily recognize objects such as windows displayed on a rear surface when displaying the objects overlapping each other.

BRIEF DESCRIPTION OF THE DRAWINGS

FIG. 1 is a block diagram illustrating a configuration example of a personal computer according to an embodiment of the present disclosure;

FIG. 2 is a diagram illustrating an example when displaying a plurality of objects overlapping each other on a display;

FIG. 3 is a flowchart for describing an object displaying process performed by the personal computer of FIG. 1;

FIG. 4 is a diagram illustrating an example when an object on a rear surface is seen;

FIG. 5 is a diagram that illustrates a configuration example of a personal computer according to a second embodiment of the present disclosure;

FIG. 6 is a block diagram illustrating a configuration example of a body in FIG. 5;

FIG. 7 is a diagram for describing details of a process performed by a face detector and an angle calculator;

FIG. 8 is a diagram for describing details of a process performed by a deforming unit;

FIG. 9 is a flowchart for illustrating a deforming process of an object performed by a personal computer of FIG. 5;

FIG. 10 is a diagram for describing another example of a detailed process performed by the deforming unit; and

FIG. 11 is a block diagram for illustrating a configuration example of a computer.

DETAILED DESCRIPTION OF EMBODIMENTS

The embodiments of the present disclosure (hereinafter, referred to as the embodiments) will be described below. Here, description will be given in the following order.

1. First Embodiment (example in a case where it is possible to see an object of a rear surface so that transparency of the object is adjusted)

2. Second Embodiment (example in a case where a location of an object is changed according to the direction in which a user sees while adjusting the transparency of the object)

3. Modified example.

1. First Embodiment

Configuration Example of Personal Computer 1

FIG. 1 illustrates a configuration example of a personal computer 1 according to the first embodiment of the present disclosure.

The personal computer 1 is configured by a body 21, a display 22, and an operation unit 23.

Here, the personal computer 1 adjusts transparencies of objects such as windows and the like displayed on the display 22, so that it is also possible to easily recognize an object of a rear surface even in a state where the objects overlap. Here, any object which can be displayed on the display 22 may display other contents except for windows, for example, documents, photographs, and moving images as the object and the like.

The body 21 adjusts transparency of each of a plurality of objects displayed on the display 22 according to an operation signal from an operation unit 23. Further, the body 21 is displayed on the display 22 by overlapping a plurality of objects in which the transparency is adjusted.

The display 22 displays a plurality of objects supplied from the body 21 overlapping each other.

The operation unit 23 is configured by operation buttons and is operated by a user. The operation unit 23 supplies a corresponding operation signal to the body 21 according to the user operation.

The body 21 is configured by a storage unit 41, a transparency adjusting unit 42, a display control unit 43, and a control unit 44.

For example, the storage unit 41 stores (maintains) a plurality of objects displayed on the display 22 in advance.

The transparency adjusting unit 42 reads out a plurality of objects from the storage unit 41. Further, the transparency adjusting unit 42 adjusts transparency of each of a plurality of read objects, for example, using a blending or the like, and supplies the plurality of objects in which the transparency is adjusted to a display control unit 43.

Here, the transparency adjusting unit 42, for example, equally adjusts transparencies of a plurality of objects, respectively. That is, for example, the transparency adjusting unit 42 adjusts respective transparencies of a plurality of objects to be translucent. In addition, for example, the transparency adjusting unit 42 may adjust the transparencies of a plurality of objects to be different values, respectively.

The display control unit 43 supplies a plurality of objects from the transparency adjusting unit 42 to the display 22, so that they are displayed overlapping each other.

The control unit 44 controls the transparency adjusting unit 42 and the display control unit 43 according to the operation signal from the operation unit 23.

That is, for example, when a user operates the operation unit 23 to focus a predetermined object of the plurality of displayed objects overlapping each other, the control unit 44 detects the predetermined attended object according to the operation signal from the operation unit 23, so that the transparency adjusting unit 42 performs a following process.

Concretely, for example, the transparency adjusting unit 42 compares the transparency of, for example, a predetermined object attended by the user of a plurality of objects with that of another object to adjust the transparency of the predetermined object to be low under control of the control unit 44.

Furthermore, for example, when the user operates the operation unit 23 to set an attention degree by which the user attends to each of a plurality of objects, the control unit 44 detects the attention degree of each of the objects according to an operation signal from the operation unit 23, so that the transparency adjusting unit 42 performs a following process.

Specifically, for example, the transparency adjusting unit 42 adjusts transparency of each of the plurality of objects according to an attention degree of the user (e.g., transparency becomes higher by reduction of the attention degree) under the control of the control unit 44.

Here, by detecting the eyes of the user with respect to a display screen of the object 22 in the personal computer 1, it may be configured so that the user detects an attended object based on the detected eyes. This is similar to a personal computer 81 to be described later.

Next, FIG. 2 is a diagram illustrating an example when displaying a plurality of objects overlapping each other on a display 22.

For example, as shown in FIG. 2, the display 22 displays a plurality of overlapped objects 61 to 63 on the front surface of a background 64, respectively.

The plurality of objects 61 to 63 are three-dimensional images, respectively, and have different depths with respect to a display screen (display surface) of the display 22.

In addition, for example, when the user operates the operation unit 23 to select an object 63 among a plurality of objects 61 to 63, the operation unit 23 supplies a corresponding operation signal to the control unit 44. The control unit 44 controls the transparency adjusting unit 42 and the display control unit 43 according to the operation signal from the operation unit 23.

That is, the transparency adjusting unit 42 reads out a plurality of objects 61 to 63 from the storage unit 41. Further, the transparency adjusting unit 42 compares transparencies of the read objects 61 to 63 with each other, adjusts the transparency of the read object 63 to be low, and supplies the plurality of objects 61 to 63 in which the transparency of each is adjusted to the display control unit 43.

The control unit 43 supplies objects 61 to 63 from the transparency adjusting unit 42 to the display 22 such that the display 22 displays the objects 61 through 63 overlapping each other. Thereby, because the object 63 is displayed in a low transparency state (deep state) and other objects 61 and 62 are displayed in a high transparency state (pale state), the user may easily recognize a selected (focused) object 63.

[Operation Description of Personal Computer 1]

Subsequently, referring to a flowchart of FIG. 3, an object display process performed by the personal computer 1 will be described.

For example, the object display process starts when an operation unit 23 is operated such that a plurality of objects 61 to 63 are displayed overlapping each other on the display 22. At this time, the controller 44 controls the transparency adjusting unit 42 and the display control unit 43 according to an operation signal from the operation unit 23.

That is, in step S21, a transparency adjusting unit 42 reads out a plurality of objects 61 to 63 from a storage unit 41. Further, for example, the transparency adjusting unit 42 adjusts transparencies of a plurality of read objects 61 to 63 using a blending and the like, and supplies a plurality of objects 61 to 63 in which the transparency is adjusted to a display control unit 43.

In step S22, the display control unit 43 provides the objects 61 to 63 from the transparency adjusting unit 42 to the display 22, so that the objects 61 to 63 are displayed overlapping each other. The foregoing object display process is ended.

As described above, according to the object display process, transparencies of objects 61 to 63 having different depths from a display screen of the display 22 are adjusted, and objects 61 to 63 after adjustment are displayed overlapping each other. Thereby, in step S22, it is possible to efficiently use a display region for displaying an image.

Further, because objects 61 to 63 having different depths in which the transparency adjusted, are displayed, even in the case where the objects 61 to 63 are displayed overlapping each other, it is possible to easily recognize any of the objects 61 to 63.

5

Next, FIG. 4 illustrates that it is possible to easily recognize display regions **62a** and **62b** on, for example, an object **62** of a plurality of objects **61** to **63**.

Here, as shown in FIG. 4, in a display region **61a** on the object **61**, for example, too many characters and the like are described, and transparencies thereof become comparatively low.

In this case, even though it is difficult to recognize display regions **62a** and **62b** on the object **62** through a display region **61a** on the object **61**, the user can easily recognize the display regions **62a** and **62b** other than the display region **61a** through a display region on an object **61**.

This causes a plurality of objects **61** to **63** to be displayed as three-dimensional images having different depths, respectively. Here, in the display **22**, it is possible to display a plurality of objects **61** to **63** having the same depth overlapping each other. However, in this case, it is desirable to display at least one of respective objects **61** to **63** to be slightly moved.

Thereby, even if displaying a plurality of objects **61** to **63** having the same depth, it is possible to more easily recognize an object of a rear surface by slight movement thereof.

Here, when moving a plurality of objects **61** to **63** by different pattern, respectively, it is possible to easily identify the objects **61** to **63**, respectively.

2. Second Embodiment

Configuration Example of Personal Computer **81**

Next, FIG. 5 illustrates a configuration example of a personal computer **81** according to a second embodiment of the present disclosure.

The personal computer **81** is configured by a camera **101**, a body **102**, a display **103**, and an operation unit **104**.

The camera **101** images a user visibly recognizing objects **61** to **63** on a display **103** in front of the display **103**, and supplies a captured image obtained by the imaging operation to the body **102**.

The body **102** detects a location of the user (e.g., locations of the face of the user, etc.) displayed on the captured image based on the captured image from the camera **101**.

Further, the body **102** performs shear deformations for a plurality of objects **61** to **63** according to the detected location of the user.

Further, the body **102** adjusts transparencies of objects **61** to **63** after shear deformation, supplies the objects **61** to **63** in which the transparency is adjusted to the display **103**, and displays the objects **61** to **63** overlapping each other.

Here, the second embodiment has illustrated performing shear deformation for example, when deforming the objects **61** to **63**. However, a deforming method when deforming the objects **61** to **63** is not limited thereto.

The display **103** displays a plurality of objects **61** to **63** supplied from the body **102** overlapping each other. Here, the second embodiment defines an XYZ coordinate space as illustrated in FIG. 5 for simplifying the description. For example, the XYZ coordinate space is defined by the X axis, the Y axis, and the Z axis indicating the horizontal direction, the vertical direction, and the front direction (depth direction) of the display **103** by using a center (center of gravity) of the display screen in the display unit **103** as an origin O.

Here, an optical axis of the camera **101** matches the Z axis in the X axis direction, and is deviated from the Z axis upward by a predetermined distance D_y in the Y axis direction.

6

[Configuration Example of Body **102**]

FIG. 6 illustrates a configuration example of a body **102**.

Here, in the body **102** of FIG. 6, the same symbols are given for portions that are configured similar to the body **21** in FIG. 1, and the description thereof will be omitted as appropriate.

That is, the body **102** is configured similarly to the case of FIG. 1 except that a face detecting unit **121**, an angle calculating unit **122**, and a changer **123** are newly provided and a control unit **124** is provided instead of the control unit **44**.

10 A captured image from the camera **101** is supplied to the face detector **121**. The face detecting unit **121** detects the face of a user displayed on the captured image based on the captured image from the camera **101**. Specifically, for example, the face detecting unit **121** detects a region of a peach color part of all regions on the captured image as a face region representing the face of the user.

Further, the face detecting unit **121** detects a face position (Ax, Ay) indicating the location of the face of the user on the captured image based on the detected face region, and supplies the detected face region to the angle calculating unit **122**. Here, for example, the face position (Ax, Ay) becomes a center of gravity in the face region. Further, the face position (Ax, Ay) is defined by the X axis and the Y axis perpendicular to an origin $(0, 0)$, for example, by using a center on a captured image as the origin $(0, 0)$.

20 Here, the X axis and the Y axis defined on the captured image are used as the X' axis and the Y' axis so as to discriminate the X axis and the Y axis illustrated in FIG. 5.

25 The angle calculating unit **122** calculates an angle θ indicating a deviation between a face position (x, y) expressing a location of the face of the user in an XYZ coordinate space and a predetermined Z axis (FIG. 5) based on a face position (Ax, Ay) from the face detecting **121**, and supplies the calculated angle θ to the deforming unit **123**.

30 That is, for example, the angle calculating unit **122** calculates an angle θ_x indicating a deviation between a face position (x, y) and the Z axis in the X axis direction and an angle θ_y indicating the face position (x, y) and the Z axis in the Y axis direction as an angle θ , and supplies the angles θ_x and θ_y to the deforming unit **123**. Here, a process performed by the face detecting unit **121** and the angle calculating unit **122** will be described with reference to FIG. 7.

35 The deforming unit **123** reads out a plurality of objects **61** to **63** from the storage unit **41**. Further, the deforming unit **123** performs shear deformations for a plurality of objects **61** to **63** read out from the storage unit **41** based on the angle θ_x and the angle θ_y from the angle calculating unit **122**, and supplies the objects **61** to **63** after the shear deformations to the transparency adjusting unit **42**. Here, a process performed by the deforming unit **123** will be described with reference to FIG. 8.

40 For example, the control unit **124** performs the same process as that of the control unit **44** in FIG. 1 according to an operation signal from the operation unit **104**. Further, the control unit **124** controls a camera **101**, a face detecting unit **121**, an angle calculating unit **122**, and a deforming unit **123**, for example, according to an operation signal from the operation unit **104**.

[Details of Face Detecting Unit **121** and Angle Calculating Unit **122**]

45 Next, referring to FIG. 7, details of a process performed by the face detecting unit **121** and the angle calculating unit **122** will be described.

50 The face detecting unit **121** detects a face region **131a** from a captured image **131** as illustrated in a right side of FIG. 7 supplied from the camera **101**. Further, for example, the face detecting unit **121** detects a center of gravity of the face region **131a** as a face position (Ax, Ay) on the captured image **131**,

and supplies the detected center of gravity of the face region **131a** to the angle calculating unit **122**. Here, for example, the face position (Ax, Ay) is defined by the X' axis and Y' axis perpendicular to an origin (0, 0) by using a center on the captured image as the origin (0, 0).

The angle calculating unit **122** normalizes (divides) Ax of the face region (Ax, Ay) from the face detecting unit **121** with a horizontal width of the captured image **131** as illustrated in a right side of FIG. 7 and converts the normalized Ax into a value d. Here, a location Ax on the X' axis representing a right end part of the captured image **131** is normalized with a horizontal width of the captured image **131** and the normalized location Ax is changed to 0.5.

Further, the angle calculating unit **122** calculates an angle θ_x by an equation (1) based on a value d obtained by normalization and a half image angle α of a horizontal direction (X axis direction) in a camera **101** as illustrated in a left side of FIG. 7, and supplies the calculated half image angle θ_x to the deforming unit **123**. Here, the angle calculating unit **122** maintains in advance an angle α in a memory (not shown) embedded therein.

$$\theta_x = \arctan\{d/(0.5/\tan \alpha)\} \quad (1)$$

Here, the angle θ_x represents a deviation between a face position (x,y) and an optical axis of (imaging direction) of the camera **101**.

Here, an optical axis of a camera **101** matches the Z axis in the X axis direction. Accordingly, the angle θ_x may present a deviation between a face position (x,y) and the Z axis in the X direction.

However, the equation (1) is obtained as follows. That is, on the Z axis, if it is assumed that a value changed according to a position z of a user face is f(z), following equations (2) and (3) are derived.

$$\tan \theta_x = d/f(z) \quad (2)$$

$$\tan \alpha = 0.5/f(z) \quad (3)$$

A $f(z) = 0.5/\tan \alpha$ is calculated by the equation (3). If it is substituted for the equation (2), a following equation (4) is derived.

$$\tan \theta_x = d/(0.5/\tan \alpha) \quad (4)$$

Further, in the equation (4), when an inverse function of $\tan \theta_x$ is obtained, the foregoing equation (1) is derived.

Further, for example, the angle calculating unit **122** normalizes (divides) Ay of a face position (Ax, Ay) from the face detecting unit **121** with a vertical width of the captured image **131**, and adds an offset value corresponding to a distance D_y to the resultant value d'' . Further, the angle calculating unit **122** calculates an angle θ_y by a following equation (5) based on a value d'' obtained by the addition and a half image angle β of the vertical direction (Y axis direction) of the camera **101**, and supplies the calculated angle θ_y to the deforming unit **123**.

$$\theta_y = \arctan\{d''/(0.5/\tan \beta)\} \quad (5)$$

Here, calculation of a value d'' by adding an offset value corresponding to a distance D_y to a value d'' is achieved by deviating an optical axis of the camera **101** from the Z axis by a distance D_y in the Y axis direction. That is, when the angle calculating unit **122** calculates an angle θ_y in a manner similar to a case where the angle θ_x is calculated, the angle θ_y does not represent a deviation between a face position (x,y) and the Z axis in an Y direction.

Accordingly, the angle calculating unit **122** calculates a value d'' by adding an offset value to the value d'' in consideration of a deviation between an optical axis and the Z axis of

the camera **101** in the Y axis direction, thereby calculating the angle θ_y by the equation (5). Further, in the captured image **131**, a distance between a location (0,y) ($y < 0$) corresponding to a three-dimensional position (0,0,z) in an XYZ coordinate space and an origin (0, 0) is a distance corresponding to a distance D_y , and the offset value becomes a value obtained by normalizing a distance between a location (0,y) and an origin (0, 0) with a vertical width of the captured image **131** in the captured image **131**.

10 [Details of Deforming Unit **123**]

Hereinafter, details of a process performed by the deforming unit **123** will be given with reference to FIG. 8.

The deforming unit **123** reads out a plurality of objects **61** to **63** stored in the storage unit **41** and deforms the read objects **61** to **63** based on angles θ_x and θ_y from the angle calculating unit **122**. Further, in FIG. 8, so as to prevent the drawing from being complicated, only the object **61** is illustrated.

That is, for example, the deforming unit **123**, as illustrated in FIG. 8, in the Z axis defining each position z of the objects **61** to **63**, axis inclines the Z by an angle θ_x from the angle calculating unit **122** compared with the axis. Thereby, for example, the x in a three-dimensional position p(x, y, z) of the object **61** becomes $x+z \tan \theta_x$.

Further, for example, in the same manner, the deforming unit **123** inclines the Z axis by an angle θ_y from the angle calculating unit **122** compared with the Y axis. Thereby, a y in a three-dimensional position p(x, y, z) of the object **61** becomes $y+z \tan \theta_y$.

By doing this, the deforming unit **123** performs an affine deformation for a three-dimensional position p(x,y,z) of the object **61** to a three-dimensional position $p'(x+z \tan \theta_x, y+z \tan \theta_y, z)$ of the object **61** to perform a shear deformation for a shape of the object **61**.

Here, actually, the deforming unit **123** performs the affine deformation for a 2D image for a left eye and a 2D image for a right eye constituting an object **61** as a three-dimensional image, respectively, and performs a shear deformation for a shape of the object **61**. Here, parallax is provided between the 2D image for a left eye and the 2D image for a right eye such that an object **61** recognized visibly by the user is three-dimensionally viewed.

Further, in the same manner, the deforming unit **123** performs shear deformations for the objects **62** and **63**, respectively.

45 The deforming unit **123** supplies the objects **61** to **63** after shear deformation to the transparency adjusting unit **42**. [Operation Description of Personal Computer **81**]

Next, referring to a flowchart of FIG. 9, an object deforming process performed by a personal computer **81** will be described.

50 Here, for example, by displaying a plurality of objects **61** to **63** overlapping each other on the display **103**, the object deforming process starts when the operation unit **104** is operated. At this time, the control unit **124** controls a face detecting unit **121**, an angle calculating unit **122**, a deforming unit **123**, a transparency adjusting unit **42**, a display control unit **43**, and a camera **101** according to an operation signal from the operation unit **104**. The camera **101** performs an imaging operation under the control of the control unit **124**, and supplies the captured image **131** obtained by the imaging operation to the face detecting unit **121**.

In step S41, the face detecting unit **121** detects a face of the user displayed on the captured image **131** based on an captured image **131** from the camera **101**. Specifically, for example, the face detecting unit **121** detects a region of a peach color part of entire regions on the captured image **131** as a face region **131a** indicating a face of the user.

Further, the face detecting unit 121 detects a face position (Ax, Ay) on the captured image 131 based on the detected face region 131a, and supplies the detected face region to the angle calculating unit 122.

In step S42, the angle calculating unit 122 normalizes Ax of a face position (Ax, Ay) from the face detecting unit 121 with a horizontal width of the captured image 131 and converts the normalized Ax into a value d. Further, the angle calculating unit 122 calculates an angle θ_x by the equation (1) based on the obtained value d by normalization and a half image angle α of a horizontal direction (X axis direction) in the camera 101, and supplies the calculated angle θ_x to the deforming unit 123.

In step S43, the angle calculating unit 122 normalizes Ay of a face region (Ax, Ay) from the face detecting unit 121 with a vertical width of the captured image 131 and converts the normalized Ay to a value d''. Further, the angle calculating unit 122 calculates and supplies an angle θ_y by the equation (5) to the deforming unit 123 based on a value d obtained by adding an offset value to the value d'' obtained by normalization and a half image angle β of the vertical direction (Y axis direction) in the camera 101.

In step S44, the deforming unit 123 reads out a plurality of objects 61 to 63 stored in the storage unit 41 from the storage unit 41. Further, the deforming unit 123 performs and supplies shear deformation for the plurality of read objects 61 to 63 to the transparency adjusting unit 42 based on angles θ_x and θ_y from the angle calculating unit 122.

That is, for example, the deforming unit 123 inclines the Z axis in an XYZ coordinate space defining a three-dimensional position of a plurality of objects 61 to 63 by an angle θ_x from the angle calculating unit 122 compared with the X axis. Further, the deforming unit 123 inclines the Z axis by an angle θ_y from the angle calculating unit 122 compared with the Y axis. Thereby, the XYZ coordinate space is deformed, and a plurality of objects 61 to 63 are also deformed by deformation of the XYZ coordinate space through deformation of the XYZ coordinate space.

In step S45, the transparency adjusting unit 42 adjusts transparencies of a plurality of objects 61 to 63 from the deforming unit 123 and supplies a plurality of objects 61 to 63 in which the transparency is adjusted to the display control unit 43.

In step S46, the display control unit 43 supplies the objects 61 to 63 from the transparency adjusting unit 42 to a display 22 such that they are displayed on the display 22 overlapping each other. The object deforming process is then ended.

As illustrated previously, in the object deforming process, angles θ_x and θ_y are calculated as an angle θ formed between the Z axis being a normal line of a display screen of a display 103 and a direction from which the user views the display screen. Further, by affine conversion for inclining the Z axis in a horizontal direction by an angle θ_x and in the vertical direction by an angle θ_y , a plurality of objects 61 to 63 are deformed.

To do this, the user may display the objects 61 to 63 to be seen on a real space regardless of a direction recognizing a display surface. Accordingly, the user may confirm, for example, an object 62 to be looked into by the user in the objects 61 to 63 displayed on the display 103.

Further, for example, because the objects 61 to 63 are displayed overlapping each other, it is possible to efficiently use a display region on the display 103 displaying an image.

In addition, for example, in an object deforming process, by changing the Z axis in an XYZ coordinate space, shear deformations for the objects 61 to 63 on the XYZ coordinate space are performed. Accordingly, for example, it is possible

to more rapidly perform a process by the deforming unit 123 by comparing a case of separately performing shear deformations for objects 61 to 63 existing in an XYZ coordinate space.

3. Modified Example

As shown in FIG. 8, a second embodiment inclines the Z axis to convert coordinates of objects 61 to 63. However, otherwise, for example, without inclining the Z axis, it is possible to convert coordinates of objects 61 to 63.

That is, for example, the deforming unit 123, as illustrated in FIG. 10, for example, a position $x (= z \tan \theta_p)$ of a three-dimensional position $p(x, y, z)$ of the object 61 is converted into an $x' (= z \tan(\theta_p + \theta_x))$ based on an angle θ_x from the angle calculating unit 122. Here, as shown in FIG. 10, an angle θ_p indicates an angle formed between a line segment combining (x, z) of a three-dimensional position $p(x, y, z)$ with an origin O and the Z axis in the XZ plane defined by the X axis and the Z axis.

Further, for example, the deforming unit 123 converts a location $y (= z \tan \theta_q)$ of a three-dimensional position $p(x, y, z)$ of the object 61 into a location $y' (= z \tan(\theta_q + \theta_y))$ based on an angle θ_y from the angle calculating unit 122 in the same manner. Here, the angle θ_q indicates a line segment combining (y, z) of a three-dimensional position $p(x, y, z)$ with an origin O and the Z axis in the YZ plane defined by the Y axis and the Z axis.

Thereby, the deforming unit 123 may converts a three-dimensional position $p(x, y, z)$ of the object 61 into a three-dimensional position $p'(x', y', z)$ to perform a shear deformation for the object 61. This may be the same as in the objects 62 and 63.

In a second embodiment of the present disclosure, a direction in which the Z axis extends matches the normal line of a display screen of the display 103, but the direction in which the Z axis extends is not limited thereto and may be changed by definition of an XYZ coordinate space.

The second embodiment has illustrated a case where a three-dimensional position $p(x, y, z)$ of each of the objects 61 to 63 is known. However, even in a case where the three-dimensional position $p(x, y, z)$ is not known (e.g., a case of a three-dimensional photograph, etc.), the present technology is applied to calculate the three-dimensional position $p(x, y, z)$.

Further, for example, the deforming unit 123 performs a shear deformation for a three-dimensional image composed of two-dimensional images (2D image for right eye and 2D image for left eye) in two observing points as a target. However, for example, the deforming unit 123 may perform a shear deformation for a three-dimensional image composed of two-dimensional images of three or more observing points as a target.

Although one camera 101 is used in the second embodiment, so as to increase a detectable range of a face region of the user, a plurality of cameras may be used to increase an image angle of the camera 101.

Further, for example, the second embodiment calculates values d and d' from a face region (Ax, Ay) on the captured image 131 obtained from the camera 101 to calculate angles θ_x and θ_y by the equations (1) to (5).

However, otherwise, for example, a face region (x, y, z) is detected as a three-dimensional position in an XYZ coordinate space, and angles θ_x and θ_y may be calculated based on the detected face region (x, y, z) and half image angles α and β of the camera 101. That is, for example, $\tan \theta_x = x/z \dots (2')$ and $\tan \alpha = g(z)/z \dots (3')$ are derived from x and z of the detected face region (x, y, z) . Further, if $\tan \theta_x = x/(g(z)/\tan \alpha) \dots (4')$ is derived from the equations (2') and (3'), $\tan \theta_x$ in the equation

11

(4'), and an inverse function of $\tan \theta_x$ is derived, $\theta_x = \text{arc tan}(x/(g(z)/\tan \alpha)) \dots (1')$ is derived. Accordingly, the angle θ_x is calculated using the equation (1'). Further, the angle θ_y is calculated by $\theta_y = \text{arc tan}(y/(g(z)/\tan \beta)) \dots (5')$ in the same manner.

Here, so as to detect a face region (x, y, z) as a three-dimensional position, a stereo camera detecting a face region (x, y, z) using the parallax of two cameras or an infrared sensor detecting a face region (x, y, z) by irradiating infrared rays and the like to a face of the user and the like are used.

In the first embodiment, although the transparency adjusting unit 42 adjusts the transparencies of all of the objects, it may adjust the transparency of only a part of the objects.

That is, for example, in a personal computer 1, in order to detect the eyes of the user with respect to a display screen of the display 22, the user determines the attended region on a display screen according to the detected eyes. Further, the transparency adjusting unit 42 may adjust the transparency of only a part of the objects 61 to 63 with respect to the determined region. This is the same as in the second embodiment.

Further, although personal computers 1 and 81 are respectively illustrated in the first and second embodiments, any of electronic devices displaying an image is also applicable to the present technology. That is, for example, the present technology is applicable to a television set for receiving and displaying an image through broadcasting electrical waves or a hard disk recorder for displaying a recorded moving image, and the like.

Here, the present technology may have a configuration as follows.

(1) A display control device includes: a changing unit changing a two-dimensional location representing locations in a horizontal direction and an orthogonal direction of each of a plurality of objects having different depths for a display screen of a display unit according to a direction in which a user views the display unit; a transparency adjusting unit for adjusting transparency for each of the plurality of objects; and a display control unit for displaying the plurality of objects in which the two-dimensional location is changed and the transparency is adjusted on the display unit, so as to overlap each other.

(2) The display control device according to the above-described (1), further includes: a detecting unit for detecting an object, to which the user focuses, of the plurality of objects, wherein the transparency adjusting unit adjusts transparency of the object to which the user attends to be lower than that of an object to which the user does not focus.

(3) The transparency adjusting unit according to the above-described (1) or (2), may adjust respective transparencies of the plurality of objects to have different values.

Incidentally, the series of processes described above may be executed by hardware or may be executed by software. In a case where the series of processes are executed by software, a program that configures the software is installed from a program recording medium onto a computer that has built-in dedicated hardware or a general-purpose computer that is able to execute various functions by installing various programs.

[Configuration Example of Computer]

FIG. 11 illustrates a configuration example of hardware of a computer for performing a series of foregoing processes by a program.

A Central Processing Unit (CPU) 141 performs various processes according to a program stored in a Read Only Memory (ROM) 142 or a storage unit 148. The program that the CPU 141 executes, data, and the like are stored as appro-

12

priate in a RAM (Random Access Memory) 143. The CPU 141, the ROM 142, and the RAM 143 are connected to each other by a bus 144.

Further, an input/output interface 145 is connected to the CPU 141 via the bus 144. An input unit 146 composed of a keyboard, a mouse, a microphone, and the like and an output unit 147 composed of a display, a speaker, and the like are connected to the input/output interface 145. The CPU 141 executes various processes according to instructions that are input from an input unit 146. Furthermore, the CPU 141 outputs the results of the processes to an output unit 147.

The storage unit 148 that is connected to the input/output interface 145 is composed, for example, of a hard disk, and stores the program that the CPU 141 executes and various pieces of data. A communication unit 149 communicates with an external device via a network such as the Internet or a local area network.

Further, a program may be obtained via the communication unit 149 and stored in the storage unit 148.

When a removable medium 151 such as a magnetic disk, an optical disc, a magneto-optical disc, or a semiconductor memory is fitted, a drive 150 that is connected to the input/output interface 145 drives the removable medium 151 and obtains a program, data, or the like that is recorded therein. The program or the data that is obtained is transferred to the storage unit 148 and stored as necessary.

As illustrated in FIG. 11, a recording medium that records (stores) a program that is installed on a computer and which is in an executable by the computer is configured by the removable medium 151 that is a packaged medium composed of a magnetic disk (includes flexible disks), an optical disc (includes CD-ROMs (Compact Disc-Read Only Memory) and DVDs (Digital Versatile Disc)), magneto optical discs (MD (Mini-disc)), a semiconductor memory, or the like, the ROM 142 in which a program is temporarily or indefinitely stored, a hard disk that configures the storage unit 148, or the like. The recording of a program on a recording medium is performed using a wired or wireless communication medium such as a local area network, the Internet, or a digital satellite broadcast via the communication unit 149 that is an interface such as a router, a modem, or the like as necessary.

Here, in the specification, the steps that describe the series of processes described above may not only be processed in a time series manner in the order described but also include processes that are executed in parallel or individually without necessarily being processed in a time series manner.

Here, the embodiments of the present disclosure are not limited to the first and second embodiments described above, and various modifications are possible within a scope of not departing from the gist of the embodiments of the present disclosure.

The present disclosure contains subject matter related to that disclosed in Japanese Priority Patent Application JP 2011-078823 filed in the Japan Patent Office on Mar. 31, 2011, the entire contents of which are hereby incorporated by reference.

It should be understood by those skilled in the art that various modifications, combinations, sub-combinations and alterations may occur depending on design requirements and other factors insofar as they are within the scope of the appended claims or the equivalents thereof.

What is claimed is:

1. A display control device comprising:

circuitry configured to

change a two-dimensional location representing locations in a horizontal direction and an orthogonal direction of each of a plurality of objects having dif-

13

- ferent depths for a display screen of a display according to a direction in which a user views the display; adjust transparency for each of the plurality of objects; and control a display to display the plurality of objects in which the two-dimensional location is changed and the transparency is adjusted so as to overlap each other.
2. The display control device according to claim 1, wherein the circuitry is configured to:
- detect an object, to which the user focuses, of the plurality of objects; and
  - adjust transparency of the object to which the user attends to be lower than that of an object to which the user does not focus.
3. The display control device according to claim 2, wherein the circuitry is configured to adjust respective transparencies of the plurality of objects to have different values.
4. A display control method of a display control device for displaying an object on a display, the method by the display control device comprising:
- changing a two-dimensional location representing locations in a horizontal direction and an orthogonal direc-

14

- tion for each of a plurality of objects having different depths for a display screen of a display according to a direction in which a user views the display; adjusting transparency for each of the plurality of objects; and controlling the display to display the plurality of objects in which the two-dimensional location is changed and the transparency is adjusted so as to overlap each other.
5. A non-transitory computer-readable medium including computer executable instructions, which when executed by an information processing device, cause the information processing device to:
- change a two-dimensional location representing locations in a horizontal direction and an orthogonal direction for each of a plurality of objects having different depths for a display according to a direction in which a user views the display;
  - adjust transparency for each of the plurality of objects; and
  - control the display to display the plurality of objects in which the two-dimensional location is changed and the transparency is adjusted so as to overlap each other.
